UNITED STATES PATENT OFFICE.

WALTER F. MATTHES, OF AUSTIN, TEXAS.

SIFTING-MACHINE.

1,270,185.

Specification of Letters Patent. Patented June 18, 1918.

Application filed November 14, 1916. Serial No. 131,246.

To all whom it may concern:

Be it known that I, WALTER F. MATTHES, a subject of the Emperor of Germany, residing at Austin, in the county of Travis 5 and State of Texas, have invented certain new and useful Improvements in Sifting-Machines; and I do hereby declare the following to be a full, clear, and exact description of the invention, such as will enable 10 others skilled in the art to which it appertains to make and use the same.

This invention relates to a sifting machine especially adapted for sifting flour, meal or the like after the initial treatment of the 15 grain to separate foreign and other material from the flour, meal or the like.

Another object of this invention is to provide a chamber within a casing to receive the material or crushed grain after the initial 20 treatment and is adapted to be thrown against a screen, whereby the flour, meal or the like will pass through the screen and be separated from the refuse.

A further object of this invention is to 25 provide a novel form of agitator having means for agitating the material or crushed grain along the entire length of the agitator, so that the material or crushed grain will be equally distributed, whereby all of the material 30 will not be thrown against one point of the screen.

A still further object of this invention is the provision of a sifting machine of the above stated character, which shall be simple, 35 durable and efficient, and which may be manufactured and sold at a comparatively low cost.

With these and other objects in view as will become more apparent as the description 40 proceeds, the invention consists in certain novel features of construction, combination and arrangement of parts as will be herein-after more fully described, and claimed.

For a complete understanding of my invention, reference will be had to the following description and accompanying drawings, in which:

Figure 1 is a vertical transverse sectional view of a sifting machine constructed in accordance with my invention,

Fig. 2 is a sectional view taken on the line 2—2 of Fig. 1, and

Fig. 3 is a fragmentary detail sectional view taken on the line 3—3 of Fig. 2.

To better illustrate and describe my invention, I have elected the employment of

three agitators and screens for the device, but do not wish to be limited as to the number of agitators and screens to be employed in the device.

Referring in detail to the drawings, the numeral 1 indicates a casing having formed in one wall thereof doorways 2 which are normally closed by removable doors 3. These doors may be readily removed from 60 the doorways 2 to give access to the interior of the casing 1 when desired. A longitudinally extending beam 4 is supported by hangers 5 to the top wall of the casing 1 and has secured thereto at one point a metallic 65 casing 6 which extends the entire width of the casing 1. The metallic casing 6 is so constructed to provide a receptacle having an inlet pipe 7 connected to one end thereof for allowing material or crushed grain to enter. 70 The upper portion of the metallic casing 6 is offset as illustrated at 8 to form a pocket 9 within the receiving receptacle for a purpose, which will be hereinafter more fully described. One edge of the metallic casing 6 75 is so formed to provide a rest as illustrated at 10 for one edge of a plurality of screen frames 11 which have secured thereto screens 12 constructed from any desired material, but preferably of silk. The upper edges of 80 the screen frames 11 abut the hangers 5 and are secured thereto by suitable catches 13 whereby the frames may be removed through the doorways 2 when desiring to clean or repair the screens upon same. A transverse 85 shaft 14 is journaled within the casing 1 and within the metallic casing 6 and has secured thereto a plurality of radially extending spokes 15 to which are secured inclined plates 16 and the plates 16 each have one of 90 their ends secured to the outermost end of the spokes and their other end secured to the next adjacent spokes at a point adjacent its outermost end so as to provide a space for supporting inclined blades 17 which are slotted 95 as illustrated at 19 and angularly arranged with relation to each other so as to cause the crushed grain or material entering one end of the receptacle formed by the metallic casing 6 to be distributed along the 100 plates 16, so that when the agitator is rotated all of the material or crushed grain 105 will not be thrown against one screen but will be distributed so as to equally engage all of the screens. As the crushed grain or material enters the receiving receptacle through the inlet pipe 7, the agitator receives same

and distributes it along its entire length and as the agitator rotates the material or crushed grain is thrown upwardly within the pocket 9 and later is caught by the agitator and 5 thrown against the screens 12, so that the flour, meal or the like within the crushed grain or material will pass through the screens into a receiving pocket 20. The flour, meal or like received within the receiving pocket 20 passes into a chute 21 that extends the entire width of the receiving pocket 20 and is inclined downwardly and communicates with a chute 22 leading to a bin or storage receptacle, whereby the flour, 10 meal or like may be received and stored. The refuse, or matter, remaining within the receiving receptacle after the flour, meal or like has been driven through the screens 12, passes outwardly through an opening 23 into 15 a chute 24 for conveying said refuse to a desired point of collection.

The second sifter located within the casing 1 is identical in construction with the above described sifter except for a few 20 changes which will be hereinafter more fully described. The second sifter consists of a metallic casing 25 forming the receiving receptacle for crushed grain or like materials, from the inlet pipe 26 at one end thereof 25 and has its upper end offset as illustrated at 27 to form a pocket 28. The screen frames 29 are identical in construction with the screen frames 11 and are secured within the casing 1 in the same manner and have the 30 screens 30 secured thereto. The agitator 31, identical to the agitator in the described sifter and is journaled within the receiving receptacle and is connected through the agitator within the first described sifter by 35 means of an endless belt 32. The agitator 31 is driven by an endless belt 33 whereby the agitators will be rotated simultaneously. As the agitator 31 is rotated the material received through the inlet pipe 26 is thrown 40 against the screen 30 and the flour, meal or the like contained therein pass into the receiving pocket 35. As the flour, meal or like, enters the receiving pocket 35 it is caught by a worm 36 and conveyed to a 45 chute 37 leading to an inlet pipe 41, the third sifter which will be hereinafter more fully described. The worm 36 is driven by an endless belt 38 connected to the shaft of the agitator 31.

50 The refuse, remaining within the receiving receptacle 25 may pass out through an opening 39 into a chute 40 and be deposited at any desired receiving point.

55 As the sifted flour, meal or like material 50 passes into the inlet pipe 41 from the worm 36 it enters the third sifter, which is of similar construction to the second sifter, consisting of a metallic casing 42 having a screen 43 of a finer mesh than the screen 30 60 and an agitator 44 similar in construction

to the agitator 31 which catches the flour or meal from the inlet pipe 41 and throws the same against the screen 43, whereby the flour or meal is again sifted, the higher grade of flour or meal entering the receiving pocket 70 45, whence it is conveyed to a storage bin in any suitable manner. The flour or meal which does not pass through the screen 43, passes out of an inlet port (not shown) and which is similar to the outer port 40 and is 75 conveyed to a storage bin. The agitator is driven by a belt connected to the shaft of the agitator 31. In operation when it is desired to use the first sifter connected with a brake, the grain after passing through the 80 brake, to receive its initial crushing, is fed into the inlet pipe 7 and agitator within the receiving receptacle throws the crushed grain against the screen 12, the flour or meal passing therethrough into the receiving 85 pocket 20 and thence into the chute 21, leading to a storage bin. In this process the flour or meal is only sifted once and when it is desired to increase the finer qualities of the flour or meal, the crushed grain from the 90 brake is passed into the second sifter by way of the inlet port 26 and the sifted flour or meal therefrom is passed into the third sifter by the worm 36 through the inlet port 46, thence it is caught by the agitator 44 95 and thrown through the screen 43 into the receiving pocket 45, thus the same flour or meal that passes through the screen 30 receives another sifting to render it of a higher grade. The flour or meal which does not 100 pass through the sifter 43 is conveyed out of the casing 42 by an outlet port (not shown) similar to the outlet port 40 of the second sifter to a bin or any other desired receptacle.

105 From the foregoing description taken in connection with the accompanying drawings, it will be noted that crushed grain after passing through a brake may be either sifted one or more times as desired to obtain different grades of flour or meal therefrom.

110 While I have shown and described the preferred embodiment of my invention, it will be understood that minor changes in construction, combination and arrangement 115 of parts may be made without departing from the spirit and scope of the invention as claimed.

Having thus described my invention what I claim is:

120 A sifting machine comprising a casing having a door way formed in one wall thereof, a hanger secured within said casing from the top wall thereof, a longitudinally extending beam secured to the hanger, a metallic member having one end secured to the beam and being bent to form a receptacle having an offset portion and an opening, and an inlet pipe connected to the offset portion of the receptacle, a screen closing the 125 130

opening of the receptacle and forming a receiving chamber between the same and the casing, an agitator journaled in the receptacle and adapted to receive crushed grain 5 from the pipe to throw the same upwardly in the offset portion to mix it and later catch the grain falling from the offset portion and throw it against the screen, an inclined chute in said casing having its upper end disposed 10 adjacent the lower edge of the screen and

extending the entire width of the receiving chamber, and a second chute connected to the opening of the receptacle.

In testimony whereof I affix my signature in presence of two witnesses.

WALTER F. MATTHES.
